ATTORNEY

UNITED STATES PATENT OFFICE.

CHARLES T. McENERY, OF SAN FRANCISCO, CALIFORNIA.

DESIGN FOR A DOLL.

59,246.

Specification for Design.

Patented Oct. 4, 1921.

Application filed March 9, 1921. Serial No. 450,979. Term of patent 14 years.

To all whom it may concern:

Be it known that I, CHARLES T. McENERY, citizen of the United States, residing in the city and county of San Francisco and State of California, have invented a new, original, and ornamental Design for Doll, of which the following is a specification, reference being had to the accompanying drawing, forming part thereof.

Figure 1, is the front view of the doll.

Fig. 2, is the rear view of the doll.

I claim:

The ornamental design for a doll, as shown.

CHARLES T. McENERY.

Witnesses:

JOHN H. HERRING,

W. W. HEALEY.
